SYSTEM OF PROTECTION OF LIQUID INSULATED ELECTRIC APPARATUS

Filed April 16, 1925

FIG. 1.

FIG. 2.

Inventor:
Max Buchholz

by Atty.

UNITED STATES PATENT OFFICE.

MAX BUCHHOLZ, OF CASSEL, GERMANY.

SYSTEM OF PROTECTION OF LIQUID-INSULATED ELECTRIC APPARATUS.

Application filed April 16, 1925, Serial No. 23,681, and in Germany February 17, 1924.

My invention has reference to a method and means for protecting electric apparatus operating in an insulating liquid, such as oil transformers, oil switches, grounding throttling coils, resistances and the like, and it is one of the important objects of my invention to provide a device of very simple construction and great reliability, and adapted to operate before extensive injuries to the apparatus to be protected can occur by sparking, overloading or other disturbances.

My invention is particularly based on the fact that in the case of disturbances in the operation of the apparatus to be protected or in the case of sparking or other irregularities of operation, or whenever such irregularities are imminent, as well as in the case of any ebullition or fermentation processes in the oil, serving as an insulating liquid, bubbles of gases of decomposition are formed which can operate a protective means, for instance an electric contact, either a working or a closed contact, which is adapted to switch out of circuit the apparatus to be protected, or which will operate an alarm or annunciator device indicating the disturbance, or which is adapted to effect both kinds of operations. The vapors generated or the gases formed by decomposition or from other causes may influence the contacting means in different ways.

No matter how the gases or vapors are caused to act on the protective means provided for cutting out the apparatus to be protected or for annunciating defects arising in consequence of an unnormal working of same, it is preferable, if not necessary, to guide the bubbles of gases or vapors rising in the liquid so as to accumulate them near the contacts or the like to be actuated.

Such accumulation of the gases or vapors can be effected in different ways, but in all cases suitable guiding surfaces must be provided.

In the drawings affixed to this specification and forming part thereof a device embodying this invention is illustrated diagrammatically by way of example. In the drawings—

Figs. 1 and 2 show an oil switch arranged in its casing which is connected with means for cutting out the switch or for annunciating a contact in case that, owing to unnormal working conditions, such defect should arise,

Fig. 1 being a vertical longitudinal section and

Fig. 2 a cross section of the apparatus.

Referring now to Figs. 1 and 2, *m* is the vessel or casing containing a supply of insulating oil *n* in which a switch *o* is disposed. In a central opening in the cover *p* closing the casing *m* is mounted a tubular extension *q* entirely filled with oil. A float *r* loosely applied against the cover of tube *q*, on descending in the oil, will meet and bridge the terminals *s* of a protective circuit comprising a switch, fuse, alarm or other annunciating device (not shown).

If, owing to an unnormal working of the apparatus, which is accompanied by the generation of heat, gases or vapors of decomposition are generated in the oil, the gas or vapor bubbles will rise in the liquid. In order to compel these bubbles to enter the tubular extension *q* and to displace some of the oil contained therein, thereby causing the float *r* to descend, guide plates *t* are arranged in sloping position on each insulator *u*, these plates being so arranged with respect to the tubular extension *q* that the gas bubbles meeting the plates are guided towards the lower opening of the tube *q*.

A similar arrangement is provided in close proximity to the switch *o*. A roof-shaped guiding member *v* is disposed right above the switch *o*. In a tubular extension *w* mounted on a central opening of the member *v* is disposed a contact flap *x* connected to one terminal of the protective circuit and capable, if lifted by gas bubbles accumulating below it, to apply itself against the other terminal *y* arranged above it. Owing to the arrangement of the guiding member *v* also the gas bubbles generated from the oil adjoining the side of the switch are compelled to accumulate below the contact flap *x*.

Besides the forms of construction herein shown and described, the invention is susceptible of a variety of other modifications and forms of application of the principle of my invention all of which operate substantially in a similar manner. The means of connecting the contacting device with the releasing circuit and the switching means are open to changes and alterations without any material importance for the operation of the apparatus according to my invention which in its broad aspects comprises the operation of safety devices for electric apparatus or the like, adapted for operation by vapors, fumes, gases or similar emanations liberated and expelled from the insulating medium,

and means adapted to be operatively influenced by such emanations, and connected to fuses or equivalent safety means, the instrumentalities shown and described in this specification as embodiments of these principles being susceptible of modifications without deviating from the spirit of my invention as set forth in the claim.

In the claim the term "gas" is meant to comprise also vapors and fumes.

I claim:

Protective system for liquid insulated elec-

tric apparatus comprising an apparatus to be protected, a container surrounding same, a supply of insulating liquid in said container, a protective circuit, comprising terminals and a contact above said apparatus and a sloping guiding surface below said contact for guiding gas developed in consequence of an abnormal operation of said apparatus towards said contact.

In testimony whereof I affix my signature.

MAX BUCHHOLZ.
